TEXTILE FABRIC OR SIMILAR ARTICLE

Marthe Meyer, Fairlawn, N. J., assignor to Lucien Forestier Corporation, New York, N. Y., a corporation of New Jersey

Application May 25, 1949, Serial No. 2,889

Term of patent 3½ years

(CL. D92—1)

To all whom it may concern:

Be it known that I, Marthe Meyer, a citizen of the United States, residing at Fairlawn, in the county of Bergen and State of New Jersey, have invented a new, original, and ornamental Design for Textile Fabric or Similar Article, of which the following is a specification, reference being had to the accompanying drawing, forming part thereof.

In the drawing the single figure is a top plan view of a textile fabric or similar article showing my new design; the design unit is outlined by broken lines and is repeated over the fabric as indicated.

I claim:

The ornamental design for a textile fabric or similar article, as shown and described.

MARTHE MEYER.
